UNITED STATES PATENT OFFICE.

LOYAL F. BAILES AND WILLIAM L. CARDEN, OF MEDFORD, OREGON.

IRONING MACHINE.

Application filed April 23, 1928. Serial No. 272,261.

The present invention relates to improvements in ironing machines and has reference more particularly to a structure that is adapted for association with a motor operated washing machine.

One of the important objects of the present invention is to provide an ironing machine that can be readily swung into or out of operative position, means being provided for locking the swingable structure in a fixed position.

A further object resides in the provision of an ironing machine, whereby the same includes a rotatable roll which has cooperating therewith a heated ironing shoe.

A still further object of the invention is to provide an ironing machine of the above mentioned character, wherein means is provided for normally maintaining the movable ironing shoe in ironing relation with respect to the roll, additional means being provided for moving the shoe away from the roll.

A still further object is to provide an ironing machine of the above mentioned character, which is simple in construction, inexpensive, strong and durable, and further well adapted to the purpose for which it is designed.

Other objects of the invention will become apparent as the nature of the invention proceeds and when taken in connection with the accompanying drawings.

In the accompanying drawings, forming a part of this application and in which like numerals designate like parts throughout the several views:

Figure 1 is a longitudinal sectional view through the ironing machine embodying our invention, parts being broken away.

Figure 2 is a sectional view, taken approximately on the line 2—2 of Figure 1, looking in the direction of the arrows for more clearly disclosing the relation between the rotatable roll and the ironing shoe, the latter being shown in an operative position with respect to the roll.

Figure 3 is a top plan view of the ironing machine, and

Figure 4 is a detail showing the hand lever

for rocking the ironing shoe supporting shaft.

In the drawings, wherein for the purpose of illustration is shown the preferred embodiment of our invention, the numeral 1 designates the base that is adapted to rest on a portion of a motor operated washing machine (not wholly shown). The portion of the washing machine upon which this base rests is shown at 2, in Figure 1 of the drawings. The drive shaft operated by the motor that actuates the washing machine extends vertically through the base for disposition at its upper end in the lower portion of the tubular standard, 4, that extends upwardly from the base, the shaft being designated by numeral 3. Formed on the upper end of the tubular standard 4 is the casing 5, which is open at its top, a removable cover 6 being provided therefor. The securing means of the cover is shown at 7, with reference more particularly to Figures 1 and 3 of the drawings.

The upper end of the vertical shaft 3 is operatively connected to the lower end of the vertical shaft 8, that extends through the upper portion of the tubular standard, and the upper end of the shaft 8 extends into the housing or casing 5. Secured on the upper end of this shaft is the bevelled gear 9.

A laterally extending sleeve 10 is formed on the inner side of the casing 5, for supporting the longitudinally extending driven shaft 11, the inner end thereof supporting the roll unit of the ironing machine, and which roll unit is designated by the numeral 12. The specific construction of the roll unit will hereinafter be more fully described. The other end portion of the horizontal shaft 11 extends through a suitable bearing or bushing 13, arranged in the opposite side of the casing 5, this particular end of the shaft 11 being reduced, and a nut 14 is threaded on the outwardly projecting end of the reduced portion 15, for disposition against the bearing 13, as is clearly illustrated in Figure 1.

The portion of the driven shaft 11 that is disposed within the casing 5 is substantially square in cross section and slidably arranged on the square portion 16 of the hori-

zontally extending driven shaft 11 and adapted for rotation therewith, is the sleeve 17, the same carrying at its respective ends, the inner opposed bevelled gears 18 and 19 respectively.

The gears 18 and 19 are selectively engageable with the driving bevelled pinion 9 for effecting the rotation of the shaft 11, in either direction.

10 The means for moving either of the bevelled gears 18 and 19 into meshing engagement with the driving pinion 9, comprises a lever 20 that is pivoted intermediate its ends as at 21, in the upper portion of the casing, 15 the inner end of the lever being operatively connected with the sleeve 17 while the outer end of the lever projects through a slot in the front side of the casing.

The outer end of the lever 20 is formed 20 with an actuating handle 22. A substantially U-shaped bracket 23 extends forwardly from the upper portion of the casing and the crown portion of this bracket is formed with a series of spaced openings 24, with which 25 cooperates a protuberance carried by the adjacent portion of the pivoted lever 20, whereby said lever may be locked in any adjusted position to either disconnect the shaft 11 from rotation with the interconnected drive shafts 30 3 and 8 or to secure either of the bevelled gears 18 and 19 in meshing engagement with the pinion 9.

A felt washer 25 encircles the horizontally disposed driven shaft 11 and is disposed 35 against the flanged end of the sleeve 10 and is secured in position by means of a retaining plate or ring 26 that is bolted or otherwise secured to the flanged end of the sleeve (see Figures 1 and 3).

40 The roll unit 12 includes a pair of end members 27 and 28 respectively, the end member 27 being arranged on the shaft 11 adjacent the flanged end of the sleeve 10, while the other end member 28 is arranged on the 45 reduced threaded extremity 29 of the shaft 11 and suitable nuts 30 and 31 are threaded on this portion of the shaft for engagement with the respective sides of the end member 28, as is clearly shown in Figure 1. The nut 50 30 and the lock nut 30' are arranged on the shaft prior to the positioning of the end member 28 on said shaft and subsequently the end member is secured in the outer end of the roll. A plurality of wooden slats 32' are arranged 55 in abutting relation between the spaced end members 27 and 28 and the ends of these wooden slats are secured to the flanged portions of the end members by any appropriate fastening means, whereby to provide a hollow wooden roll 32 which may be covered 60 with a piece of cloth or other suitable covering designated by the numeral 33. The roll unit will rotate with the horizontally disposed driven shaft 11.

65 The ironing machine embodying our in-

vention further comprises the provision of a curved ironing shoe 34 that is hollow and is furthermore adapted to cooperate with the rear portion of the covered wooden roll 32. The hollow ironing shoe 34 is adapted to be 70 heated by placing heating coils 35 within the shoe that are electrically heated, or if desired, the hollow ironing shoe may be heated by gas. The ironing shoe is of a length substantially equivalent to the length of the roll 75 32, and a suitable handle bar 36 extends upwardly from the central portion of the upper edge of this ironing shoe.

This ironing shoe is supported by a vertically disposed arm 37, the upper end portion 80 of which is curved and which is secured to the bottom edge portion of the ironing shoe at the central portion thereof by any suitable fastening means, such as is shown at 38, with reference to Figure 2. The lower end of 85 the supporting arm 37 is disposed within a socket 39 that extends upwardly from a sleeve 40, the latter being adjustably secured on the outer end of a rockable rod 41. A set screw 42 is threaded through a transverse opening formed in this sleeve 40 for engagement with the rockable rod 41 to secure the sleeve in any adjusted position thereon.

The inner end of the rockable arm 41 extends through a laterally disposed housing 43, formed on the intermediate portion of the tubular standard 4 and the inner extremity of the rockable rod is journaled in a suitable socket 44, formed in the housing 43, as clearly illustrated in Figure 1. The intermediate portion of the housing 43 is formed with a cut-out portion 45 that intersects the longitudinal bore formed in said housing, for accommodating the inner end portion of the rockable lever 52.

100 A torsional coil spring 46 encircles the intermediate portion of the rockable rod 41, one end of the coil spring being secured to an axial pin 47 that projects from the outer end of the housing 43, while the other end of said coil spring is connected to a pin 48 that projects from a collar 49 adjustably secured on the rod 41 through the medium of the set screw 50.

110 By adjusting the collar 49 on the rod 41, the tension of the coil spring 28 may be regulated. A suitable covering 51 is provided for the spring 46 and the collar 49, as is also clearly shown in Figure 1 of the drawings. The purpose of the coil spring is to provide 120 a means for normally holding the swingable ironing shoe in ironing relation with respect to the rotatable roll 32. The shoe may be moved rearwardly away from the roll by pushing rearwardly on the handle bar 36 or 125 by actuating the forwardly extending lever 52 that is secured at its inner end in the portion of the rockable rod 41 located at the cut out portion 45. The outer end of the lever 52 is formed with a handle portion 53.

A substantially U-shaped bracket 54 is arranged vertically, and the free ends of the arms thereof are secured to the standard 4, and the intermediate portions of the arms are 5 bent so as to dispose the crown portion of the bracket in close proximity to the intermediate portion of the lever and the crown portion of said U-shaped bracket is formed with an indentation or opening 55, with which co- 10 operates a protuberance 56, carried by the adjacent portion of the lever, so that said lever may be held in position, to lock the rockable rod against rocking movement when the ironing shoe is moved away from the 15 roll 32.

For the purpose of locking the ironing machine against swinging movement on the washing machine, we provide a vertically moveable locking rod 57, that has its upper 20 end extending into a socket 58, formed in the bottom portion of the casing 5, and an expansible coil spring 59 is arranged in the socket between the closed end thereof and the upper end of the rod for normally urging 25 said rod downwardly. The lower end of the rod is removably disposed within registering openings formed in the base 1 and the portion 2 of the washing machine.

By raising this rod 57 upwardly so that 30 the lower end of the rod is moved out of the opening in the portion 2 of the washing machine, the ironing machine 10 may be swung out of the way to permit the use of the washing machine or the wringer, (not shown) 35 that is associated with the washing machine in the conventional manner.

It will thus be seen from the foregoing 40 description, that we have provided an ironing machine that is capable of being mounted upon a washing machine so that the motor that is employed for driving the washing machine can be utilized for actuating the ironing machine and due to its simplicity, the parts comprising our ironing machine 45 can be readily and easily assembled and operated:

While we have shown the preferred embodiment of our invention, it is to be understood that minor changes in the size, shape, 50 and arrangement of parts may be resorted to, without departing from the spirit of the invention and the scope of the appended claims.

Having thus described our invention, what we claim as new is:

- 55 1. In an ironing machine of the class described, a rotatable shaft, a roll secured on the shaft for rotation therewith, a rockable shaft arranged in spaced relation with respect to the roll carrying shaft, a laterally extending arm secured on the rockable shaft, an ironing shoe carried by the outer end of said arm, means associated with the rockable shoe for maintaining the ironing shoe normally in ironing relation with respect to the

rotatable roll, and additional means for 65 actuating the rockable shaft to move the ironing shoe away from the roll, said first mentioned means including a torsional coil spring encircling the rockable shaft, one end of said spring being secured to a stationary 70 support, the other end of the coil spring being secured to the rockable shaft.

2. In an ironing machine, a base, a tubular standard extending upwardly therefrom, a casing on the upper end of the tubular standard, a sleeve extending laterally from one side of the casing, a housing extending laterally from the intermediate portion of the standard, a drive shaft arranged in the standard, a driven shaft journaled in said sleeve, 80 one end of said shaft extending into said casing, a driving connection between the drive and driven shafts, an ironing roll secured on the outer end of the shaft for rotation therewith, a rockable shaft having its inner end 85 supported in said housing, a laterally extending arm secured at one end to the outer end of the rockable shaft, an ironing shoe secured on the other end of the lateral arm for cooperation with the rotatable roll, a torsional coil spring encircling the intermediate 90 portion of the rockable shaft, one end of said coil spring being secured to the outer end of the housing, an adjustable collar secured on the rockable shaft outwardly of the housing, 95 the other end of the coil spring being secured to said collar for normally holding the ironing shoe in ironing relation with respect to the rotatable roll, and means for actuating the rockable shaft for moving the ironing 100 shoe away from the roll.

3. In an ironing machine, a base, a tubular standard extending upwardly therefrom, a casing on the upper end of the tubular standard, a sleeve extending laterally from one side of the casing, a housing extending laterally from the intermediate portion of the standard, a drive shaft arranged in the standard, a driven shaft journaled in said sleeve, one end of said shaft extending into said casing, a driving connection between the drive and driven shafts, an ironing roll secured on the outer end of the shaft for rotation therewith, a rockable shaft having its inner end supported in said housing, a laterally extending arm secured at one end to the outer end of the rockable shaft, an ironing shoe secured on the other end of the lateral arm for cooperation with the rotatable roll, a torsional coil spring encircling the intermediate portion of the rockable shaft, one end of said coil spring being secured to the outer end of the housing, 110 an adjustable collar secured on the rockable shaft outwardly of the housing, the other end of the coil spring being secured to said collar for normally holding the ironing shoe in ironing relation with respect to the rotatable roll, and means for actuating the rockable shaft for moving the ironing 115 shoe away from the roll.

the rockable shaft for moving the ironing shoe away from the roll, said last mentioned means comprising a laterally extending lever secured at its inner end to the rockable shaft, 5 a bracket, and cooperating means between said lever and said bracket for holding the rockable shaft in such position as to main-

tain the ironing shoe out of ironing relation with respect to the rotatable roll.

In testimony whereof we affix our signatures.

LOYAL F. BAILES.
WILLIAM L. CARDEN.
